Primary Examiner — Ricky Pham*(74) Attorney, Agent, or Firm* — Price Heneveld LLP**CLAIM**

The ornamental design for a food processing device, as shown and described.

DESCRIPTION

FIG. 1 is a front-right perspective view of a food processing device according to the design;

FIG. 2 is a back-right perspective view thereof;

FIG. 3 is a front-left perspective view thereof;

FIG. 4 is a left perspective view thereof; and,

FIG. 5 is a front-right perspective view thereof showing the food processing device mounted with an environmental article.

Dash-dot-dash broken lines are environmental only and form no part of the claimed design.

The portions of the article shown in evenly-dashed broken line form no part of the claimed design.
